Primary Examiner — Darlington Ly(74) *Attorney, Agent, or Firm* — Reinhart Boerner Van Deuren P.C.(57) **CLAIM**

The ornamental design for a right angle drill attachment, as shown and described.

DESCRIPTION

FIG. 1 is a perspective view of a right angle drill attachment showing our new design;

FIG. 2 is a top plan view thereof;

FIG. 3 is a front elevation view thereof;

FIG. 4 is a rear elevation view thereof;

FIG. 5 is a side elevation view thereof;

FIG. 6 is an opposing side elevation view thereof; and,

FIG. 7 is a bottom plan view thereof.

The broken lines in the drawings illustrate portions of the right angle drill attachment that form no part of the claimed design.
